FLEXIBLE LOOP ANTENNA

William J. Schnell, Berwyn, Ill., assignor to Electrical Research Laboratories, Inc., Evanston, Ill., a corporation of Illinois

Application May 8, 1941, Serial No. 392,480

12 Claims. (Cl. 250—16)

This invention relates to radio receiving apparatus and more particularly to portable radio receivers.

A primary object of the invention is the provision of a portable radio receiving apparatus provided with a readily connectible and disconnectible external loop antenna which may be easily carried in a pocket or the like and is readily and quickly attachable and detachable with respect to a supporting surface such as a window or the like.

A further object is the provision of a flexible loop antenna that is simple and inexpensive in construction, which may be readily folded and lies substantially flat for carrying in a pocket or the like, which is readily connected to and disconnected from a portable radio receiver, and which is quickly and easily attached to and detached from a supporting surface.

A further object is the provision of such flexible loop antenna that gives substantially unobstructed clear vision through a window or the like when attached thereto.

A further object is the provision of a novel connecting means for readily connecting and disconnecting a flexible external loop antenna to and from a radio receiving apparatus.

A further object is the provision of portable radio receiving apparatus having a built-in antenna, an external loop antenna adapted for connection to the receiving apparatus, and novel means for disconnecting the built-in antenna when the external antenna is connected.

These and other objects will be apparent from the following description, the appended claims and the accompanying drawing in which

Fig. 1 is a perspective view of a portable receiver having an external loop antenna constructed in accordance with the present invention connected thereto and attached to a window of a vehicle;

Fig. 2 is a perspective view partly broken away, of the flexible loop antenna shown in Fig. 1;

Fig. 3 is an enlarged sectional view taken on the line 3—3 of Fig. 2;

Fig. 4 is an enlarged sectional view taken on the line 4—4 of Fig. 2;

Fig. 5 is an enlarged detailed section taken on the line 5—5 of Fig. 2;

Fig. 6 is a fragmentary elevational view showing a portion of the inside of the radio receiving apparatus of Fig. 1 and illustrating a switch in position therein for disconnecting a built-in antenna when the flexible loop antenna is connected to the apparatus, the view being taken

from the rear of the front control panel as seen in Fig. 1; and

Fig. 7 is a view looking upwardly at the switch of Fig. 6 as indicated by the arrow in Fig. 6 and having the antenna connections diagrammatically illustrated therein.

Referring to the drawing which illustrates a selected embodiment of the invention and in which like reference characters designate like parts in the several views, there is shown a small, compact, portable radio receiving set 10 comprising a housing or casing 11, a control panel 12, a hinged door 13, and a strap 14 providing for ready transportation of the apparatus. A radio receiving apparatus of any desired structure and design is mounted within the casing 11, and an arm 15 of a snap switch extends outwardly through a suitable opening in the side of casing 11 and provides for turning the set "on" and "off." The door, 13, is adapted to be latched shut when the apparatus is not in use to cover the front control panel 12.

To provide for normal reception of radio waves an antenna 20 is built into the set 10 and in the illustrated embodiment comprises a spirally wound conductor mounted within the door 13. The antenna 20 is electrically connected with the receiving apparatus within the casing 11 by means of the door hinges 21 as shown in Fig. 6 of the drawing. Under normal conditions of use, the antenna 20 provides for receiving radio signals and effecting operation of the set 10.

It is often desirable, however, to operate the receiving set 10 within a metallic shielding structure, such as an automobile, aeroplane, train and the like, and under such conditions of use the built-in antenna 20 is ineffective for proper reception and operation of the set. To provide for proper operation of the receiving apparatus under such conditions of use, or at any other time that the built-in antenna 20 is ineffective for proper reception, an external flexible loop antenna 25 is provided and may be readily connected to the set and also attached to a supporting surface such as a window. The loop antenna 25, furthermore, is of such construction that it may be readily folded into a very flat and compact mass adapted to be easily carried in a pocket or the like and which when attached to a window gives substantially clear unobstructed vision therethrough.

Referring to Figs. 2 and 4 the antenna 25 comprises a plurality of turns of insulated wire 26 arranged side by side and enclosed within inner and outer bands of relatively thin, wide, flexible material 27 and 28. The bands 27 and 28 are of

sufficient width to extend laterally outwardly beyond the turns of wires 26 as indicated at 29 and a suitable adhesive is applied to the inner surfaces of the bands to adhesively secure the bands to the wires 26 and the portion 29 of the bands to each other. The bands 27 and 28 are also preferably stitched together at the portions 29 as indicated at 30, Fig. 4.

The overlying bands 27 and 28 together with the turns of wire 26 enclosed therein form a relatively thin, band-like loop as shown in Figs. 1 and 2. To provide for readily attaching and detaching the loop with respect to a supporting structure such as a window, a flap 35 is sewed or otherwise attached to the loop and is secured as indicated at 36, to a vacuum cup 37. The arrangement of this flap 35 and vacuum cup 37 with respect to the loop 25 is of primary importance with respect to one feature of the invention.

As clearly shown in Figs. 1 and 2 this arrangement is such that when the vacuum cup 37 is attached to a window or the like, the width of the band-like loop extends substantially normal to the plane of the supporting surface and only the relatively thin side edge of the loop lies parallel with the window. This thin side edge, furthermore, is in the form of an entirely opened loop. There is thus substantially clear unobstructed vision through the window and the attachment of the antenna does not materially detract from vision through the window.

The turns of wires 26 forming the loop antenna are adapted to be connected to the set 10 by a pair of flexible lead wires 40 and 41 which are connected to opposite ends of the wires 26 and are enclosed within thin, ribbon-like strips of flexible material 42 similar to the material 27-28. The ribbon-like strips 42 preferably have a width corresponding to the width of bands 27 and 28 and are suitably connected to these bands as indicated at 43 in Fig. 2. The inner surfaces of the strips 42 are adhesively secured together as indicated at 44 to properly enclose the lead wires 40 and 41 and also to maintain these wires in substantially spaced relationship, as shown in Fig. 3, to reduce the capacity between them and thereby increase the tuning range. The strips 42 are also preferably stitched together externally of the wires 40 and 41 as illustrated at 45, Fig. 3.

The antenna 25 is adapted to be readily connected to and disconnected from the set 10 by means of a pair of plug tips 50 adapted to be received in cooperating sockets provided in the top of the set housing 11. As shown in Figs. 2 and 5 the end of the strips 42 remote from the loop 25 are provided with a stiffening member 51 such as fiber board, and which is enclosed within the strips by sewing or the like. The plug tips 50 extend outwardly from one side of the stiffening member 51 and are provided with hollow bores 52. A screw 53 having a head 54 extends through the member 51 from the other side thereof and has a threaded portion 55 which is press-fitted within the bore 52 of the plug tip 50. The threaded portion 55 of screw 53 has a slightly larger diameter than the bore 52, and thus by press-fitting the screw into the plug tip bore a very simple, inexpensive and yet rigid and normally undetachable connection is made between the plug tips and the strips 42. To provide an electrical connection between the lead wires 40 and 41 and the plug tips 50, the wires are wound around the screws 53 of the respective plug tips

and secured beneath the heads 54 of the screws as indicated at 56, Fig. 5.

To provide for proper operation of the radio set 10 when the loop antenna 25 is attached thereto, a means is provided for automatically disconnecting the built-in antenna 20 upon insertion of the plug tips 50 within the sockets provided on the top portion of the housing 11. This means also provides for operatively connecting the loop antenna with the radio receiving apparatus contained within the housing 11.

As shown in Figs. 6 and 7, this means comprises an elongated base member 60 of suitable insulating material which is attached to a top wall of the housing 11 by means of studs 61 and nuts 62. The base 60 is provided with openings 63 which align with opening 64 provided in the top of the housing 11 (see Fig. 6) and are adapted to receive the extended reduced end portions 65 of the plug tips 50. The portions 65 of plug tips 50 are adapted to extend downwardly beyond the inner face of the base member 60 and a pair of spring contact clips 66 and 67 are mounted on the insulated base in position to be engaged by the plug tips when inserted through the openings 63 and 64. Each of the contact clips 66 and 67 comprises a substantially U-shaped member having spring contact fingers 68 extending inwardly and downwardly therefrom. The respective pairs of contact fingers 68 extend relatively close to each other at their lower ends and are provided with curved portion 69 adapted to engage around the plug tip and provide a good electrical connection therewith. The diameter of the portion 65 of the plug tips is also such that the spring fingers 68 are spread somewhat apart upon insertion of the plug tips, thereby insuring a good electrical connection between the plug tips and contact clips.

An electric conducting bracket 75 is secured to the base 60 between the contact clips 66 and 67 and supports a leaf spring 76 of electrical conducting material which extends across the tops of the contact clips and tends to bend downwardly into contact therewith. The contact spring 76 thus normally engages and provides an electrical contact with the top of the spring clip 67 as shown in Fig. 7, but is prevented from making electrical contact with the spring clip 66 by a sheet of insulating material 77 which extends around the clip and over the top thereof between the clip and spring contact member 76. A member 78 attached to the bracket 75 extends across a portion of the top of the contact spring 76 and assists in causing the spring to tend to bend downwardly into contact with the clip 67. A cam member 80 of suitable insulating material is fixedly attached to the end of the spring member 76 adjacent the contact clip 67 as indicated at 81 and extends downwardly between the spring arm 68 of the clip. Upon insertion of a plug tip into the contact clip 67, the portion 65 of the plug engages cam member 80 and causes it to lift contact spring 76 out of contacting engagement with clip member 67. Upon withdrawal of the plug tip from the clip 67, the contact member 76 springs back into contact with the clip 67.

The operation of this plug receiving and switching means is best described in connection with the wiring connections diagrammatically illustrated in Fig. 7. The wires I-1 and I-2 indicate the input wires which are connected to the built-in antenna 20 by means of hinges 21. The wire I-1 is directly connected to the contact clip 66 while the wire I-2 is connected to the bracket

75 and thus to the contact spring 76 by medium of the bracket. The wires O-1 and O-2 indicate the connections from the plug receiving and switch means to the radio apparatus contained within the set housing 11. The wire O-1 is directly connected to the contact clip 66 while the wire O-2 is directly connected to the contact clip 67. Thus the built-in antenna 20 is normally connected to the receiving apparatus by means of wire I-1, contact clip 66 and wire O-1 on one side and wire I-2, bracket 75, spring contact member 76, clip 67 and wire O-2 on the other side. When the plug tips 50 are inserted in the clips 66 and 67, however, to connect the loop antenna 25 to the set, the contact spring 76 is raised out of engagement with clip 67 by means of cam 80, and the built-in aerial 20 is thereby disconnected. At the same time the loop antenna is connected to the receiving apparatus by the electrical contact between the plug tips 50 and clips 66 and 67 to which the wire O-1 and O-2 are connected, a condenser 90 is connected to the bracket 75 and the contact clip 66.

A portable radio receiving set is thus provided that is adapted to operate properly under different and all kinds of conditions of use, and an external loop antenna is provided that can be readily and quickly attached to a supporting surface such as a window of a vehicle and which is simply and easily connected to and disconnected from the receiving set. The loop antenna, furthermore, is in the form of a relatively thin band having substantially circular shape and mounted on the supporting surface in such manner that the width of the band extends substantially normal to the surface. Vision through the window is thus substantially unimpaired. The construction of the loop antenna is such that it is very light in weight and may be readily flattened and folded into a small compact flat mass which can be readily carried in a pocket or the like. The wires 26 and the adhesively secured enclosing bands 28 and 29 provide sufficient stiffness and resiliency to hold the loop open and substantially circular in shape when in use, while permitting flattening and folding of the loop when it is desired to carry the same. The band members 28, 29, and 42 may also be water-proofed or otherwise treated to increase the stiffness and maintain the loop and lead-in portion substantially flat across the width thereof. A novel switch means is also provided for disconnecting an antenna built into the set when the external loop antenna is connected to the receiver.

Changes may be made in the form, construction, and arrangement of the parts without departing from the spirit of the invention or sacrificing any of its advantages, and the right is hereby reserved to make all such changes as fairly fall within the scope of the following claims.

The invention is hereby claimed as follows:

1. A loop antenna of the character described adapted for ready attachment to a window or the like and providing for substantially unobstructed clear vision through said window or the like comprising a relatively wide and thin band-like member forming a circular loop, said member comprising overlying sheets of flexible material, a plurality of turns of flexible wire enclosed in said band-like member, the inner surfaces of said sheets being adhesively secured to said wires and to each other, a lead-in member extending from the wide flat side of said loop and comprising two overlying portions of rela-

tively wide and thin flexible material, a pair of flexible lead wires connected to said turns of wires and enclosed within said lead-in member, the inner surfaces of said portions of the lead-in member being adhesively secured together to maintain said lead wires enclosed therein and spaced apart, said loop and said lead-in member thereby forming a unitary flexible structure adapted to be arranged in flat position for folding and the like, plug means connected to said lead wires and adapted for connection to a radio receiver at the end of said lead-in member, and suction means connected with said band-like member for attaching said loop to a window or the like with the width of the band-like member extending substantially normal to the plane of the window or the like.

2. A loop antenna of the character described adapted for ready attachment to a window or the like and providing for substantially unobstructed clear vision through said window or the like comprising a relatively wide and thin band-like member forming a circular loop, said member comprising overlying sheets of flexible material, a plurality of turns of flexible wire enclosed in said band-like member, the inner surfaces of said sheets being adhesively secured to said wires and to each other, said sheets extending laterally outwardly beyond opposite sides of said turns of wires, stitching on the outwardly extending portions of said sheets to assist in holding the sheets together and enclosing said turns of wires, a lead-in member extending from the wide flat side of said loop and comprising two overlying portions of relatively wide and thin flexible material, a pair of flexible lead wires connected to said turns of wires and enclosed within said lead-in member, the inner surfaces of said portions of the lead-in member being adhesively secured together to maintain said lead wires enclosed therein and spaced apart, said loop and said lead-in member thereby forming a unitary flexible structure adapted to be arranged in flat position for folding and the like, plug means connected to said lead wires and adapted for connection to a radio receiver at the end of said lead-in member, and suction means connected with said band-like member for attaching said loop to a window or the like with the width of the band-like member extending substantially normal to the plane of the window or the like.

3. A loop antenna of the character described adapted for ready attachment to a window or the like and providing for substantially unobstructed clear vision through said window or the like comprising a relatively wide and thin band-like member forming a circular loop, said member comprising overlying sheets of flexible material, a plurality of turns of flexible wire enclosed in said band-like member, the inner surfaces of said sheets being adhesively secured to said wires and to each other, said sheets extending laterally outwardly beyond opposite sides of said turns of wires, stitching on the outwardly extending portions of said sheets to assist in holding the sheets together and enclosing said turns of wires, a lead-in member extending from the wide flat side of said loop and comprising two overlying portions of relatively wide and thin flexible material, a pair of flexible lead wires connected to said turns of wires and enclosed within said lead-in member, the inner surfaces of said portions of the lead-in member being adhesively secured together to maintain said lead wires enclosed therein and spaced apart, stitching along the side edges of said

lead-in member and externally of said lead wires to assist in holding said sheet portions together and enclosing the lead wires, said loop and said lead-in member thereby forming a unitary flexible structure adapted to be arranged in flat position for folding and the like, plug means connected to said lead wires and adapted for connection to a radio receiver at the end of said lead-in member, and suction means connected with said band-like member for attaching said loop to a window or the like with the width of the band-like member extending substantially normal to the plane of the window or the like.

4. A loop antenna of the character described adapted for ready attachment to a window or the like and providing for substantially unobstructed clear vision through said window or the like comprising a relatively wide and thin band-like member forming a circular loop, said member comprising overlying sheets of flexible material, a plurality of turns of flexible wire enclosed in said band-like member, the inner surfaces of said sheets being adhesively secured to said wires and to each other, said sheets extending laterally outwardly beyond opposite sides of said turns of wires, stitching on the outwardly extending portions of said sheets to assist in holding the sheets together and enclosing said turns of wires, a lead-in member extending from the wide flat side of said loop and comprising two overlying portions of relatively wide and thin flexible material, a pair of flexible lead wires connected to said turns of wires and enclosed within said lead-in member, the inner surfaces of said portions of the lead-in member being adhesively secured together to maintain said lead wires enclosed therein and spaced apart, said lead-in member having substantially the same width as said band-like member to provide for maintaining said lead-wires in substantial spaced relationship, said loop and said lead-in member thereby forming a unitary flexible structure adapted to be arranged in flat position for folding and the like, plug means connected to said lead wires and adapted for connection to a radio receiver at the end of said lead-in member, and suction means connected with said band-like member for attaching said loop to a window or the like with the width of the band-like member extending substantially normal to the plane of the window or the like.

5. A loop antenna of the character described adapted for ready attachment to a window or the like and providing for substantially unobstructed clear vision through said window or the like comprising a relatively wide and thin band-like member forming a circular loop, a plurality of turns of flexible wire enclosed in said band-like member, a lead-in member extending from the wide flat side of said loop and comprising two overlying portions of relatively wide and thin flexible material, a pair of flexible lead wires connected to said turns of wires and enclosed within said lead-in member, said loop and said lead-in member thereby forming a unitary flexible structure adapted to be arranged in flat position for folding and the like suction means connected with said band-like member for attaching said loop to a window or the like with the width of the band-like member extending substantially normal to the plane of the window or the like, a reinforcing member attached to said lead-in member at the end thereof remote from said loop, and a pair of plugs receivable within a radio receiver attached to said reinforcing member and connected to said lead wires.

6. A loop antenna of the character described adapted for ready attachment to a window or the like and providing for substantially unobstructed clear vision through said window or the like comprising a relatively wide and thin band-like member forming a circular loop, a plurality of turns of flexible wire enclosed in said band-like member, a lead-in member extending from the wide flat side of said loop and comprising two overlying portions of relatively wide and thin flexible material, a pair of flexible lead wires connected to said turns of wires and enclosed within said lead-in member, said loop and said lead-in member thereby forming a unitary flexible structure adapted to be arranged in flat position for folding and the like suction means connected with said band-like member for attaching said loop to a window or the like with the width of the band-like member extending substantially normal to the plane of the window or the like, a reinforcing member attached to said lead-in member at the end thereof remote from said loop, a pair of plugs receivable within a radio receiver attached to said reinforcing member and connected to said lead wires, each of said plugs comprising a female portion having a hollow bore and receivable on one side of said reinforcing member, and a threaded bolt-like member receivable from the opposite side of said reinforcing member and press-fitted into said hollow bore of the female portion.

7. In an antenna of the character described providing for ready attachment and detachment with respect to a radio receiver, a loop antenna, flexible lead wires connected to said loop antenna, means for connecting said lead wires to a radio receiver comprising a reinforcing member, a plug member having a hollow bore and receivable on one side of said reinforcing member, and a threaded bolt-like member receivable from the opposite side of said reinforcing member and press-fitted into said hollow bore of the plug member.

8. In a radio receiving apparatus of the character described, a portable radio receiving set, an antenna built into said set, socket means on said set for receiving a pair of plugs from an external antenna, clip members in said set for engaging and electrically connecting said plugs to the receiving apparatus, a spring member normally engaging one of said clip members and having electrical contact therewith, an insulated member on said spring member extending into the path of movement of one of said plugs into one of said clip members and providing for electrically disconnecting said spring member from said clip member upon insertion of said plug in the said clip member, and an electrical connection between said built-in antenna, said spring member and the other one of said clip members whereby the built-in antenna is normally connected to the receiving apparatus and is disconnected when said external antenna is attached.

9. In a radio receiving apparatus of the character described switch means for disconnecting a built-in antenna and connecting an external antenna, comprising a pair of clip members for receiving plug members on said external antenna and providing for electrically connecting the external antenna to the radio receiving apparatus, a spring member normally engaging one of said clip members and having electrical contact therewith, an insulated member on said spring member extending into the path of movement of one of said plugs into one of said clip members and

providing for electrically disconnecting said spring member from said clip member upon insertion of said plug in the said clip member, and an electrical connection between said built-in antenna, said spring member and the other one of said clip members whereby the built-in antenna is normally connected to the receiving apparatus and is disconnected when said external antenna is attached.

10. An antenna comprising a circular strip of material having a plurality of turns of wire enclosed therein to provide a loop antenna, lead-in conductors connected to the free ends of the loop wire and adapted for connection to a radio receiver, said conductors being spaced, an elongated strip of tape material encasing the conductors and connected to the strip enclosing the circular antenna whereby there is provided a single one-piece antenna and lead-in construction having a circular portion at its upper end and an extension lead-in connection, the material encasing the antenna and lead-in being flexible whereby the entire device may be arranged in flat position for folding and the like.

11. An antenna comprising a circular strip of material having a plurality of turns of wire enclosed therein to provide a loop antenna, lead-in conductors connected to the free ends of the loop wire and adapted for connection to a radio receiver, said conductors being spaced, an elongated 30 strip of tape material encasing the conductors

and connected to the strip enclosing the circular antenna whereby there is provided a single one-piece antenna and lead-in construction having a circular portion at its upper end and an extension lead-in connection, the material encasing the antenna and lead-in being flexible whereby the entire device may be arranged in flat position for folding and the like, and a suction cup attached to said circular strip of material.

12. An antenna comprising a circular strip of material having a plurality of turns of wire enclosed therein to provide a loop antenna, lead-in conductors connected to the free ends of the loop wire and adapted for connection to a radio receiver, said conductors being spaced, an elongated 15 strip of tape material encasing the conductors and connected to the strip enclosing the circular antenna whereby there is provided a single one-piece antenna and lead-in construction having a circular portion at its upper end and an extension lead-in connection, the material encasing the antenna and lead-in being flexible whereby the entire device may be arranged in flat position for folding and the like, a suction cup attached to 20 said circular strip of material, and plug means carried by said elongated strip of tape material and electrically connected with said lead-in conductors for connecting the antenna to the radio receiver.

WILLIAM J. SCHNELL.
